UNITED STATES PATENT OFFICE.

JAMES WHIITE JOHNSON, OF NORTHVIEW, VIRGINIA.

DUMPING-WAGON.

SPECIFICATION forming part of Letters Patent No. 710,868, dated October 7, 1902.

Application filed February 11, 1902. Serial No. 93,547. (No model.)

To all whom it may concern:

Be it known that I, JAMES WHITE JOHNSON, a citizen of the United States, residing at Northview, in the county of Mecklenburg, 5 State of Virginia, have invented certain new and useful Improvements in Dumping-Wagons; and I do hereby declare the following to be a full, clear, and exact description of the invention, such as will enable others skilled 10 in the art to which it appertains to make and use the same.

This invention relates to dumping-wagons; and it has for its object to provide a wagon of this nature which will be particularly 15 adaptable to farm uses and which will be simple and durable in construction.

A further object of the invention is to provide a construction of wagon wherein at whatever point the body may be tilted within certain 20 limits an efficient support will be provided and one which will hold the body from complete removal from the running-gear.

Other objects and advantages of the invention will be understood from the following 25 description.

In the drawings forming a portion of this specification, and in which like numerals of reference indicate similar parts in the several views, Figure 1 is a side elevation showing 30 the wagon with the body tilted into dumping position. Fig. 2 is a rear end elevation of the wagon with the body raised to its carrying position.

Referring now to the drawings, there is 35 shown a wagon comprising a running-gear including wheels 5, front and rear hounds 6, reach 7, and bolsters 8. Upon the bolsters 8 are disposed the longitudinal sills 9 and 10, having suitable connecting cross-pieces and 40 in which are bearings for the ends of axles 11, on which are disposed, in pairs, supporting rollers or wheels 12 for the body proper of the wagon.

The body proper of the wagon consists of 45 the bottom 13, to which are connected the end 14 and the sides 15, and across the bottom of the body are secured the cleats 16, against the under sides of which and extending longitudinally of the body at the side edges there- 50 of are secured the rails 17, which in the present instance are cross-sectionally L-shaped to engage the supporting-rollers 12, so that

the body is held against lateral displacement from the running-gear while being free to slide longitudinally thereof. To hold the 55 body normally against movement upon the rollers 12, sockets 20 are secured to the outer faces of the sills 9 and 10 and other sockets 21 are secured to the sides of the wagon-body and the rails, respectively, the last-named 60 sockets being positioned to register with the sockets of the sills to receive in connection therewith retaining-pins 22. The retaining-pins being raised from the sockets of the sills, the body of the wagon may be pushed rearwardly to project from the running-gear, and when pushed to the proper extent the body 65 will move into tilted position, as shown in Fig. 1 of the drawings. To hold the body from slipping entirely from the running-gear 70 when pushed rearwardly to tilt while permitting the body to tilt, upwardly-directed hooks 25 are secured to the rear ends of the sills, the hooks extending rearwardly beyond the sills and projecting thereabove. Upon 75 the outer faces of the tracks or rails 17 are secured the racks 26, the teeth of which project downwardly and the sockets of which are of such dimensions as to permit of engagement of the rounded upper ends of the 80 hooks therewith. The body of the wagon being pushed rearwardly, it will finally move into tilted position, depending upon the distribution of the load, and when this tilting occurs the racks are moved into engagement 85 with the hooks, which latter act not only as fulcrums for the body, but prevent further rearward movement of the body. After the load has been dumped the front end of the body is depressed to raise the body, when the 90 rails engage the rearmost rollers and upon them as fulcrums are raised, disengage the racks from the hooks, after which the body may be slid along the rollers to its former position and the retaining-pins reengaged with 95 all of the sockets.

With this construction it will be noted that at whatever point of its sliding movement the body be tilted within the limits of the racks the hooks will be engaged, the racks being 100 sufficiently long in practice to insure engagement each time.

In practice modifications of the specific construction shown may be made and any suit-

able materials and proportions may be used for the various parts without departing from the spirit of the invention.

What is claimed is—

- 5 1. A dumping-wagon comprising a running-gear, a body slidably mounted upon the running-gear and adapted to tilt therefrom, fulcrum-pieces carried by one of said members and a series of sockets carried by the other
- 10 member for each fulcrum-piece, each series of sockets lying spaced from its corresponding fulcrum-piece when the body is in sliding contact with the running-gear and adapted to interchangeably receive its corresponding
- 15 fulcrum-piece when the body is tilted at different points of its sliding movement.
2. A dumping-wagon comprising a running-gear provided with rollers, a body mounted upon the rollers for movement to project
- 20 therebeyond to permit of tilting of the body, fulcrum-pieces carried by the running-gear and projecting from the rear end thereof and

a series of sockets secured to each side of the body in position to lie spaced from its corresponding fulcrum-piece when the body is in ²⁵ position upon the rollers and adapted to interchangeably receive its corresponding fulcrum-piece when the body is tilted at different points of its sliding movement.

3. A dumping-wagon comprising a running-³⁰ gear including sills provided with rollers, hooks upon the sills projecting rearwardly and upwardly therefrom, a body having tracks or rails engaged with the rollers for longitudinal movement thereon to project ³⁵ rearwardly therefrom into tilting position, and racks upon the body for engagement with the hooks when the body is tilted.

In testimony whereof I affix my signature in presence of two witnesses.

JAMES WHITE JOHNSON.
